UNITED STATES PATENT OFFICE.

ANGELOS KURTIS, OF BROOKLYN, NEW YORK.

LIFE-PRESERVING SUIT.

Application filed October 4, 1924. Serial No. 741,739.

To all whom it may concern:

Be it known that I, ANGELOS KURTIS, a citizen of the United States, residing at Brooklyn, in the county of Kings and State 5 of New York, have invented certain new and useful Improvements in a Life-Preserving Suit, of which the following is a specification.

This invention relates to improvements in 10 life preserving garments and has for its principal object to provide a suit which may be easily and readily applied to the body and worn in case of an emergency while on a ship.

Another important object of the invention 15 is to provide the life preserving suit of the above mentioned character which will be water tight whereby the wearer of the same will be held above a surface of the 20 water.

Another important object of the invention is to provide a life preserving suit of the above mentioned character, which is simple in construction; inexpensive, strong 25 and durable and furthermore adapted for the purposes for which it is designated.

Other objects and advantages of this invention will become apparent during the course of the following description.

In the accompanying drawing forming a 30 part of this specification and in which like numerals designate like parts throughout the same:

Figure 1 is a view partly in elevation and 35 partly in section of the life preserving suit embodying my invention.

Figure 2 is a sectional view taken approximately on line 2—2 of Figure 1.

Figure 3 is a side elevation of the waist 40 line encircling member, and

Figure 4 is a view of the outer waist line encircling band.

In the drawing wherein for the purpose 45 of illustration is shown the preferred embodiment of my invention, the numeral 1 designates the shirt portion, the same being formed preferably of rubber and lined with cloth or any other suitable material. The neck portion 2 thereof is adapted to fit 50 snugly around the neck of the wearer. The sleeves 3 of the shirt portion are provided at their ends with the hand coverings 4. The trousers portion is designated by the numeral 5 and the legs 6 thereof are provided at their lower ends with the foot coverings 7. The lower portion of the

jacket or shirt 1 is adapted to extend over the upper portion of the trousers 5 in the manner clearly illustrated in Figure 1. The trousers portion is also formed of rubber 60 and may be lined with any suitable lining in a manner similar to the shirt or jacket 1.

For the purpose of holding the jacket 1 and the trousers 5 in airtight and water proof relation, the waist line encircling band 8 is provided. The same comprises the complementary sections 9 and 10 respectively, the respective ends of which are provided with interfitting portions through which extend the locking pin 11 in the manner 65 clearly illustrated in Figures 1 and 2 of the drawing. When the locking pins 11 are in position in the interfitting ends of the complementary sections 9 and 10, the waist line encircling member 8 will be supported in 70 proper position on the body of the wearer and on the inside of the life preserving garment. Each of the sections of the waist line encircling member 8 is provided on its outer 75 face with the ribs 12 and the purpose of these ribs is to provide a means for engagement with the overlapping portions of the jacket and trousers in the manner clearly 80 illustrated in Figure 1. The portions of the overlapping portions of the jacket and trousers which are disposed adjacent the ribs 85 will be forced outwardly to provide the bulged portions 13 and 14.

A retaining belt 15, preferably of leather, is adapted to extend around the waist line 90 of the person wearing the life preserving garment on the outside of the garment and the usual fastening means 16 and 17 is associated with the respective ends of the belt. Arranged on the inner face of the belt 15 95 are the ribs 18.

The rubber ribs or strips 18 associated with the inner face of the belt 15 cooperates with the bulged portions 13 and 14 respectively of the life preserving garment in 100 further rendering the garment water proof at the juncture of the jacket and the trousers. The garment is adapted to be inflated by any suitable pump such as is carried in the pocket 19 provided on the jacket 105 1 therefor, the pump being illustrated at 20. An inflating valve 21 is associated with the jacket for connection to the pump in order to permit the jacket and trousers to be inflated with air. An inflatable tube 22 extends around the jacket or shirt portion 1 110 and the same is also provided with an in-

flating valve 23. An additional pocket 24 is provided in the jacket or shirt portion for receiving a receptacle 25 in which is contained drinking water.

5 If desired, the trousers may be supported on the body of the wearer by providing the suspender straps 26.

A life preserving suit of the above mentioned character, may be readily and easily 10 put on and inflated whenever it becomes necessary such as in the case of a ship wreck and when the suit is inflated as well as the core 22, the wearer will be kept afloat upon the water. The simplicity in 15 which my improved life preserving suit is constructed enables the same to be manufactured at a very low cost and will further be efficient in carrying out the purposes for which the same is designated.

20 While I have shown the preferred embodiment of my invention, it is to be understood that various changes in the size, shape and arrangement of parts may be resorted to without departing from the spirit of the 25 invention and the scope of the appended claims.

Having thus described the invention, what I claim is:—

1. In a life preserving suit comprising 30 an inflatable jacket, hand coverings on the ends of the sleeves of the jacket, an inflatable trousers portion, foot coverings on the lower ends of the legs thereof, the adjacent ends of the jacket and trousers portion being 35 arranged in overlapping relation, means encircling the waist line of the wearer for holding the jacket and trousers portion in air tight and water tight relation, said means comprising complementary sections

40 detachably secured together at their respective ends and arranged on the inside of the suit, ribs on the outer face of said sections for engagement with the overlapping portions of the jacket and trousers, and a band 45 extending around the waist line on the outside of the garment, and means associated with the band for cooperation with the bulged portions of the overlapping portions of the jacket and trousers formed by the 50 ribs on the complementary sections.

2. In a life preserving suit comprising an inflatable jacket, hand coverings on the ends of the sleeves of the jacket, an inflatable trousers portion, foot coverings on the lower ends of the legs thereof, the adjacent ends 55 of the jacket and trousers portion being arranged in overlapping relation, means encircling the waist line of the wearer for holding the jacket and trousers portion in air tight and water tight relation, said 60 means comprising complementary sections detachably secured together at their respective ends and arranged on the inside of the suit, ribs on the outer face of said sections for engagement with the overlapping portions of the jacket and trousers, and a band 65 extending around the waist line on the outside of the garment, means associated with the band for cooperation with the bulged portions of the overlapping portions of the jacket and trousers formed by the ribs on the complementary sections, 70 said last mentioned means comprising rubber strips arranged on the inside of said band.

75 In testimony whereof I affix my signature.

ANGELOS KURTIS.
